LIGHT SIGNAL FOR RAILROADS

Oscar S. Field, Rochester, N. Y., assignor to General Railway Signal Company, Rochester, N. Y.

Original application September 8, 1931, Serial No. 561,802, which is a division of application Serial No. 128,437, August 10, 1926. Divided and this application October 16, 1937, Serial No. 169,422

2 Claims. (Cl. 248—278)

The present application is a division of my pending application Ser. No. 561,802, filed September 8, 1931, for Light signals, now Patent No. 2,103,251 dated December 28, 1937, which latter application was a division of application Ser. No. 128,437, filed August 10, 1926, now Patent No. 1,835,150, dated December 8, 1931.

This invention relates to new improvements in light signalling apparatus.

10 An object of the invention is to provide a means for adjustably mounting a light signal on a signal pole, so that the emitted beam can be readily directed in any direction and retained securely in adjusted position.

15 With this and other objects in view, as may be more readily apparent from the following specification, and appended claims, I will now proceed to describe one embodiment of my invention. In the drawing:

20 The single figure is a cross section through a signal in accordance with this invention, showing the interior mechanism in side elevation.

The basic principle of the signal which comprises the utilization of a source of light together 25 with means for concentrating said source through a second focal point, passing this light through a screen through this focal point and then projecting the same from a lens, is old in the art. The present invention consists more particularly of 30 improved methods of construction and combination of the apparatus rather than in the basic light projection idea.

The optical principle above referred to in this embodiment comprises a source of light 1 in combination with an elliptical reflector 2 which is adapted to collect and concentrate the rays from the source of light 1 to a focal point 3. At 35 this focal point colored spectacles or other screens are movably mounted and have the effect of changing the color or beam characteristic in accordance with the particular screen then intercepting the beam. The beam then diverges to cover a lens which is adapted to project the rays in a substantially parallel beam. In the present

40 embodiment of the invention the source of light 1 and reflector 2 are carried in a holder 7 which is mounted in the cover 8 of the mechanism case 3, thereby making this part of the signal removable with the mechanism.

45 The construction of the signal generally is as follows: An outer or main case 10 is provided and is equipped with a rear door 11 suitably hinged thereto at 12 and adapted to be locked in place by means of a latch 13 which engages with 50 the pin 14 in the case, being held in engagement

by means of a spring 15. A sealing gasket 16 is provided in such a manner that it will be compressed when the nut 17 is tightened down over the latch member 13, thereby making the case substantially water tight. A hasp 18 and staple 5 19 are provided so that the case may be suitably locked to prevent unauthorized tampering with the mechanism.

The front of the main case is provided with a recess 20 in which is mounted a suitable lens 5 10 with a sealing gasket 21 adapted to exclude moisture and dust. Where it is considered desirable, a spacer ring 22 is provided which in its turn has a recess 23 adapted to carry a spreader cover glass 24, this also being properly gasketed as 15 shown at 25. In order to hold this spreader glass in place, the combination hood and lens ring 26 is provided, the whole assembly being held together by means of suitable screws 27 which pass through the members into tapped holes in the 20 main case.

Attached to the hood ring 26 is a suitable hood 28 adapted to screen the surface of the spreader glass, or the lens where the spreader glass is not being used, from the direct rays of the sun thereby substantially eliminating reflection of white light from these surfaces. On the top of the main case 10 a casting 29 is provided having upwardly extending parts 30 and 31 respectively. The part 30 is provided with a peephole 32 and the part 31 is provided with a hole 33 and a co-acting sight member 34 which will be described hereafter. The axes of the two holes 32 and 33 are arranged to be substantially parallel with the axis of the light beam. 35

Attached to the front of the signal case by means of suitable bolts 35 and spacers 36 is a suitable background 37 preferably made of sheet steel properly protected against corrosion. It is the purpose of this background to provide a 40 black contrasting surface around the light when the signal is viewed in the day time, particularly when the angle of vision projects above the sky-line.

The interior of the case is suitably painted 45 with a black paint of low reflecting qualities in order to substantially eliminate reflection of light from the interior of the signal. It is further provided with suitable lugs 38 having holes 39 located therein which are adapted to properly locate the mechanism 40 in relation to the lens 5. The mechanism 40 is provided with suitable studs 41 adapted to engage in the holes 39 for this purpose.

In order that the signal may be properly 55

aligned along the track, a special bracket member 48 is provided adapted to be clamped to the signal pole 49 at any desired point around or along the pole, by means of suitable U bolts 50 or 5 in any other desirable manner. The hinge supporting member 51 is provided and is equipped with a downwardly extending fixed stud 52 adapted to pass through a hole 53 in bracket 48 which extends outwardly and away from the 10 pole, and is provided with locking nuts 54, whereby the bracket member may be rotated about the vertical axis of stud 52 while bearing on 48, and locked in any suitable position by means of the nuts 54. By this arrangement provision is made 15 for adjusting the direction of the projected beam in a horizontal plane. In order to adjust the beam in a vertical plane, the mechanism is pivoted to the hinge member 51 by means of suitable pivots 55. The front end of the main case 10 is 20 provided with a downwardly extending fixed stud 56 equipped with adjusting nuts 57. A forwardly extending arm member 58, bifurcated at its outer end, is adapted to pass between the nuts 57 and about stud 56, thereby providing means 25 whereby the signal may be adjusted and locked in a vertical plane.

The upper surface of the end part of 58 is formed with a spherical surface to match and always be in contact with the lower spherical surface of the upper nut 57. As the center of gravity of the case is to the right of pivots 55, the case can be adjusted by first turning down lower nut 57, then turning upper nut 57 in one or the other direction, and then tightening up on lower nut 57.

A wire outlet opening is provided in the main case 10 at 59 and a flexible conduit 60 may be used to protect the wires passing out of the signal case to the pole 49 and then through the nipple 61 into the hole in the well known manner.

While I have described one embodiment of the invention, it is well understood that many departures can be made from the specific details of the structure without departing from the 45 spirit of the invention.

Having described my invention, I now claim:

1. In a support bracket for adjustably supporting light signal casings and the like on signal poles, in combination, a curved plate, clamp means for adjustably clamping the plate to a pole 5 at any desired point on the pole, a bracket extending from the outer face of the plate, an arm, means pivoting the arm to a casing, a stud fixed to the arm, a bore in the bracket snugly and rotatably receiving the stud, matching faces on 10 the bracket and the arm, means for clamping the stud against rotation in the bore, an extending finger on the arm, an elongated open ended slot in the finger extending at right angles to the pivot for the arm, a stud fixed to the casing and passing through the slot, a clamp nut on the casing stud 15 having a spherically curved face, a matching spherically curved face on the finger at the position of the slot with the two curved faces 20 contacting, and a clamp nut on the casing stud on the side of said finger opposite to the curved face.

2. In a support bracket for adjustably supporting light signal casings and the like on signal poles, in combination, a curved plate, clamp 25 means for adjustably clamping the plate to a pole at any desired point on the pole, a bracket integral with, and extending from, the outer face of the plate, an arm, means pivoting the arm to a casing, a stud fixed to the arm, a bore in the bracket snugly and rotatably receiving the stud, matching contacting concave-downwardly-facing spherical faces on the bracket and the arm, means for clamping the stud against rotation in the bore, an extending finger on the arm, a stud 30 fixed to the casing, an elongated open ended slot in the finger extending at right angles to the pivot for the arm, the casing stud passing through the slot, a clamp nut on the casing stud having a spherically curved face, a matching 35 spherically curved face on the finger at the position of the slot with the two curved faces contacting, and a clamp nut on the casing stud on the side of said finger opposite to the curved face.

OSCAR S. FIELD. 45
